Hugo De Alteriis, New York, N. Y.

Application October 9, 1944, Serial No. 115,687

Term of patent 7 years

(Cl. D45—19)

To all whom it may concern:

Be it known that I, Hugo De Alteriis, a citizen of the United States of America, residing in New York city, county of New York and State of New York, have invented a new, original, and ornamental Design for a Brooch Pin or Similar Article, of which the following is a specification, reference being had to the accompanying drawing, forming part thereof, wherein,

Figure 1 is a front elevational view of a brooch pin or similar article showing my new design.

Figure 2 is a side elevational view of the brooch pin or similar article shown in Figure 1.

I claim:

The ornamental design for a brooch pin or similar article, substantially as shown.

HUGO DE ALTERIIS.
